(57) **CLAIM**

The ornamental design for a camera mount, as shown and described.

DESCRIPTION

FIG. 1: A side perspective view of a camera mount showing my new design, in a closed position.

FIG. 2: A side perspective view of the camera mount in a closed position.

FIG. 3: A side perspective view of the camera mount in a closed position.

FIG. 4: A side perspective view of the camera mount in a closed position.

FIG. 5: A front view of the camera mount in a closed position.

FIG. 6: A rear view of the camera mount in a closed position.

FIG. 7: A top view of the camera mount in a closed position.

FIG. 8: A bottom view of the camera mount in a closed position.

FIG. 9: An underside perspective view of the camera mount in a closed position.

FIG. 10: An underside perspective view of the camera mount in a closed position.

FIG. 11: An underside perspective view of the camera mount in a closed position.

FIG. 12: An underside perspective view of the camera mount in a closed position.

FIG. 13: A top perspective view of the camera mount in a closed position.

FIG. 14: A top perspective view of the camera mount in a closed position.

FIG. 15: A top perspective view of the camera mount in a closed position.

FIG. 16: A top perspective view of the camera mount in a closed position.

FIG. 17: A side perspective view of the camera mount in an open position.

FIG. 18: A side perspective view of the camera mount in an open position.

FIG. 19: A side perspective view of the camera mount in an open position.

FIG. 20: A side perspective view of the camera mount in an open position.

FIG. 21: A front view of the camera mount in an open position.

FIG. 22: A rear view of the camera mount in an open position.

(Continued)

FIG. 23: A top view of the camera mount in an open position.
FIG. 24: A bottom view of the camera mount in an open position.

FIG. 25: An underside perspective view of the camera mount in an open position.

FIG. 26: An underside perspective view of the camera mount in an open position.

FIG. 27: An underside perspective view of the camera mount in an open position.

FIG. 28: An underside perspective view of the camera mount in an open position.

FIG. 29: A top perspective view of the camera mount in an open position.

FIG. 30: A top perspective view of the camera mount in an open position.

FIG. 31: A top perspective view of the camera mount in an open position; and,

FIG. 32: A top perspective view of the camera mount in an open position.
